(57) **CLAIM**

The ornamental design for a hood air intake screen, as shown and described.

DESCRIPTION

FIG. 1 is a perspective view of a hood air intake screen according to our new design;

FIG. 2 is a front view of the hood air intake screen of FIG. 1;

FIG. 3 is a top view of the hood air intake screen of FIG. 1;

FIG. 4 is bottom view of the hood air intake screen of FIG. 1;

FIG. 5 is a left side view of the hood air intake screen of FIG. 1; and,

FIG. 6 is a right side view of the hood air intake screen of FIG. 1.

The rear of the hood air intake screen is unornamented.

The broken lines immediately adjacent the shaded areas as depicted in the FIGURES, represent the bounds of the claimed design while all other broken lines are directed to environment and are for illustrative purposes only; the broken lines form no part of the claimed design.

FIGS. 1-6 illustrate a first embodiment of our novel design suitable for use on the left side of a vehicle. Our novel design also includes a second embodiment suitable for use on the right side of a vehicle, which is mirror symmetrical to FIGS. 1-6 and therefore not separately illustrated.

1 Claim, 4 Drawing Sheets
